(57) **CLAIM**

The ornamental design for an aquarium, as shown and described.

DESCRIPTION

FIG. 1 is a front elevational view of an aquarium showing my new design;

FIG. 2 is a rear elevational view thereof;

FIG. 3 is a left side view thereof;

FIG. 4 is a right side view thereof;

FIG. 5 is a top plan view thereof; and,

FIG. 6 is a bottom plan view thereof.

The broken lines shown in the figures represent portions of the aquarium that form no part of the claimed design.
